UNITED STATES PATENT OFFICE.

GILMAN R. COBURN, OF CHELSEA, MASSACHUSETTS.

DESIGN FOR A HEEL-MOLD.

SPECIFICATION forming part of Design No. 20,786, dated June 2, 1891.

Application filed March 23, 1891. Serial No. 386,136. Term of patent 14 years.

To all whom it may concern:

Be it known that I, GILMAN R. COBURN, a citizen of the United States, residing at Chelsea, in the county of Suffolk and State of Massachusetts, have invented and produced a new and original Design for a Heel-Mold, of which the following is a specification, reference being had to the accompanying drawings, forming part thereof, in which—

10 Figure 1 is a plan view of a heel-mold, showing my design; and Fig. 2 is a side elevation of the same, these two views being deemed necessary to fully illustrate my design.

Similar figures of reference indicate corresponding parts in both views.

The leading feature of my design consists in the oval oblong figure produced in relief on the face of the mold and the inclined marginal surface between the oblong figure and the sides and back of the mold.

15 10 is the mold, the top of which, when viewed in elevation or plan, appears to be formed of the two concentric lines 11, the surface 13 of the mold between the lines 11 having the appearance of being inclined when viewed in 25 side elevation, and the oval oblong figure formed by the inner concentric line 11 being produced in relief and having an oval appearance when viewed in side elevation. The top surface 12 of the mold is traversed transversely at one end by a bead-like figure 14, which is produced in relief thereon.

I claim—

20 The design for a heel-mold herein shown and described.

GILMAN R. COBURN.
